UNITED STATES PATENT OFFICE

2,362,232

COMPENSATOR

Rudolph J. Anschicks, Chicago, Ill., assignor to
Protectoseal Company of America, Inc., Chi-
cago, Ill., a corporation of Illinois

Application April 15, 1943, Serial No. 483,115

8 Claims. (Cl. 277—71)

My invention belongs to that general class of devices known as valves and relates particularly to a novel form of valve, either a single or double check valve. The valve is particularly adapted for use as a check valve in a pipe line or conduit to control or break up pressure waves or surges of fluid in the line from any cause. Normally the valve is open permitting unrestricted flow of the fluid through the conduit, but is automatically operative to check a wave or surge and then when relieved to permit the flow to be unrestrictedly reestablished.

The invention has among its objects the production of a simple, inexpensive, durable, efficient and dependable check valve of the kind which is not subject to sticking because of corrosion or from non-use or becoming inoperable under sudden or excessive pressures.

The device has as a further object the production of a device which will substantially cushion the shock of a surge of liquid, break up the surge and reset itself, operating in a succession of checking actions if required and gradually relieving the pressure.

The device as illustrated is a double check valve operating in either direction, to stop a surge from either side, and at the same time operative to expedite the release of fluid into the low pressure side should it be required. The invention may be embodied in a single check for breaking up a surge from a single direction.

Many other objects and advantages of the construction herein shown and described will be obvious to those skilled in the art from the disclosure herein given.

To this end my invention consists in the novel construction, arrangement and combination of parts herein shown and described and more particularly pointed out in the appended claims.

In the drawing wherein like reference characters indicate like or corresponding parts:

Fig. 1 is a sectional view illustrating the embodiment of my invention in a double check showing the parts in their normal position.

Fig. 2 is a similar view showing the parts in changed positions, and Fig. 3 is a cross section taken on the line 3—3 of Fig. 1.

As shown, 1 generally represents a housing or portion of a conduit of the desired size, shape and material. The particular housing shown consists of a part 3 constructed for connection with a conduit or the like (not shown) and 4 represents a similar part arranged at 5 for connection to a cooperating conduit or part (not shown). These two parts may be secured together

in any suitable manner, as shown, they threadedly engage each other, which construction facilitates assembly of the unit. Arranged within the housing is a partition or wall 6 which may be threaded as at 6' to engage one of the housing parts as shown at 4 or otherwise secured in place. This partition 6 is provided with an opening through the same affording communication between the housing chambers 11 and 12 at the two sides of the partition. Arranged within the housing and carried by the partition 6 is a helical or coiled spring element 8 of the desired size and shape and of suitable material and resiliency. Normally, the coils of the spring are separated or open as indicated at 9. As shown, the spring is mounted in the partition with one end in one chamber 11 and the other end in the other chamber 12, and the free ends are closed by caps 10. The spring may be supported or maintained in place in the housing by threading the same in the partition 6 at the opening. The caps may be likewise secured in place. It is immaterial whether the spring is one continuous spring or two springs with their ends abutting in the partition. The spring should be of such size or proportion that the area between the coils is as great or greater than the area of the housing inlet port so as to normally permit free flow through the same. It will be noted that the chambers 11 and 12 are of a size not to restrict the passage of the fluid through the same and about the spring valve and caps.

In use, the device is connected in a system as for example connected at each end to the adjacent ends of conduits in a pipe line. Normally, fluid may flow through the housing from one end to the other as for example through one end 14 and out through the end 15, it being immaterial which is the direction of flow. We may assume that the direction is as indicated by the arrow at the end 14. Normally, the fluid flows into the housing and between the coils at 9 to the interior of the spring and thence through the spring and out through the spaces 9 at the opposite side in chamber 12 and out through 15. In case of a sudden surge of fluid through the conduit into the housing as for example due to an explosion or for some other reason, the surge pressure will cause the spring in chamber 11 to contract closing the space between the coils substantially as shown in Fig. 2, the various coils constitute substantially a helical valve with the adjacent coils seating upon each other and closing the passages. At the same time the excessive pressure initially passing through the spring can be relieved with-

in the spring by the spring end in chamber 12 extending as shown at the left of Fig. 2. Ordinarily, the spring in chamber 11 will then extend or restore itself after the surge is over and the end in chamber 12 contract or restore itself so that the parts take their normal positions as shown in Fig. 1, which are their normal operating positions.

Obviously, the device constitutes a double-acting check valve operative to stop or control surging from either direction. It is, of course, obvious that the spring may be provided in only one chamber as for example 11 and omitted in chamber 12 or vice versa depending on which is the pressure side. The spring may be constructed in two parts, one in each chamber and if desired may be of different strength or tension. While I have shown a helical spring with the coils of circular cross-section, obviously any other cross-sectional shape of wire making up the coil may be employed. Any means for guiding the spring in its movements may be provided, a simple and satisfactory construction consisting of ribs, lugs or pins 20 on the caps, or similar ribs (not shown) on the interior of the housing.

From the preceding, it will be obvious that the device normally does not interfere with the free passage of fluid through the housing. In the event, however, of a surge, its progress will be checked, and thereafter the coils will tend to again open up to permit free circulation through the conduit.

Having thus described my invention, it is obvious that various modifications may be made in the same without departing from the spirit of my invention; hence, I do not wish to be understood as limiting myself to the exact form, arrangement, and combination of parts herein shown and described or uses mentioned.

What I claim as new and desire to secure by Letters Patent is:

1. In a double action check valve of the kind described, a housing provided with openings for the passage of fluid through the same, a transverse stationary partition having an opening therethrough, disposed between said housing openings dividing the housing into two associated communicating chambers, a helical spring closed at its ends and arranged in said partition with one end in one chamber and the other end in the other chamber, the coils of the spring normally spaced apart to permit unrestricted passage of fluid through the housing and the coils in each chamber seating upon each other when the closed spring end in that chamber is subjected to a sudden surge of fluid toward the partition, whereby to close the passages between the coils in that chamber.

2. In a double action check valve of the kind described, a housing arranged for connection in a pipe line and to constitute a part thereof and provided with openings for the passage of fluid to and from the same, a stationary partition having an opening through the same and disposed between said first mentioned openings dividing the housing into two associated communicating chambers, a helical spring closed at its ends and connected to said partition at the opening therethrough with one end in one chamber and the other end in the other chamber, the coils of the spring in both chambers normally spaced apart to normally permit unrestricted passage of fluid through the spring and housing and the coils in each chamber seating upon each other when the closed spring end in that chamber is subjected to

a sudden surge of fluid toward the partition, whereby to close the passages between the coils in that chamber.

3. In a check valve of the kind described and in combination, a housing provided with openings for the admission and discharge of fluid to or from the housing and an apertured stationary partition dividing the housing into a plurality of communicating chambers and means for controlling the passage of fluid between the chambers consisting of a helical spring closed at each end and mounted in the aperture in the partition with one end in one chamber and the other end in the other chamber, the coils of the spring normally spaced apart to permit passage of fluid through the housing and the coils in each chamber seating upon each other when the closed spring end in that chamber is subjected to a sudden surge of fluid toward the partition, whereby to close the passages between the coils in that chamber.

4. A check valve of the kind described and in combination, a housing provided with ports for the admission and discharge of fluid through the housing and means for controlling movement of fluid through the casing consisting of a helical spring mounted in the housing and extending toward the admission port, said spring being closed at the end adjacent the admission port and arranged at the opposite end to communicate with said discharge port, the coils of said spring normally spaced from each other, but contractable to close upon an abnormal surge of fluid into the housing through the admission port, and cooperating means between the closed end of the spring and housing wall for limiting transverse movement of the closed end of the spring.

5. In a check valve of the kind described and in combination, a housing constructed for connection with a conduit and provided with ports communicating with the conduit for admitting fluid to the interior of the housing and discharge therefrom, a stationary partition having an opening therethrough and arranged in the housing separating the same into two associated communicating chambers, a helical spring mounted in said opening in said partition and projecting into each chamber, each free end of the spring provided with a closure, the coils of the said spring normally spaced apart to permit communication between the two chambers through the said spaces, said spring constituting means for controlling the passage of fluid between the chambers whereby upon excessive pressure in one chamber due to fluid surge in one direction, the coils in said chamber will tend to close the spaces between them, and the coils in the other chamber will extend.

6. In a check valve of the kind described and in combination, a housing arranged for connection to a conduit and providing a portion of the conduit, a stationary partition arranged within the housing dividing the same into two chambers, said partition having an opening for communication between the chambers, a helical spring arranged within the housing and carried by the wall of said opening in said partition with a portion of the spring in one chamber and a further portion in the other chamber, the coils of said spring normally spaced apart, and a cap or closure on each of the free ends of the spring, whereby an excessive fluid surge against one side of the cap in one chamber causes the spring to contract in said one chamber and expand in the other.

7. In a check valve of the kind described and

in combination, a housing having an admission chamber and a discharge chamber arranged for connection to a conduit and providing a portion of the conduit, a stationary partition arranged within the housing dividing the same into two chambers, said partition having an opening for communication between the chambers, a helical spring arranged within the housing and carried by the wall of said opening in said partition with a portion of the spring in one chamber and a further portion in the other chamber, the coils of said spring normally spaced apart, a cap or closure on each of the free ends of the spring, the said spring operable to contract in the admission chamber and to expand in the discharge chamber, and means for guiding the free ends of the spring.

8. In a double action check valve, a housing provided with openings at its ends for the passage

of fluid through the housing, a stationary partition having an opening therethrough, disposed between said housing openings and dividing the housing into two associated communicating chambers, a helical spring threadedly mounted midway between its ends in the partition, with its end portions extending respectively into the two chambers, caps one mounted on each end of the spring and closing said end, the coils of said spring normally being spaced apart to permit unrestricted passage of fluid through the housing, but the coils in either chamber being capable of seating upon each other to close the passage through the partition upon a sudden surge of fluid against the cap on that portion of the spring contained in the chamber in which the surge occurs.

RUDOLPH J. ANSCHICKS.
